(57) CLAIM

The ornamental design for a key blank as shown and described.

DESCRIPTION

FIG. 1 is a Perspective View of the key blank;
FIG. 2 is a Front View thereof;
FIG. 3 is a Rear View thereof;
FIG. 4 is a Right Side View thereof;
FIG. 5 is a Left Side View thereof;
FIG. 6 is a Top Plan View thereof;
FIG. 7 is a Bottom View thereof; and,
FIG. 8 is a partially enlarged view taken along 8-8 in FIG. 1.

The portions of the key blank shown in dash-dot broken lines form no part of the claimed design. The dash-dot lines illustrate boundaries between the claimed portions and unclaimed portions.

1 Claim, 8 Drawing Sheets
